UNITED STATES PATENT OFFICE

GEORGE J. MEUER, OF MILWAUKEE, WISCONSIN, ASSIGNOR TO CUTLER-HAMMER, INC.,
OF MILWAUKEE, WISCONSIN, A CORPORATION OF DELAWARE

APPLIANCE PLUG CLIP OR TERMINAL

Application filed July 9, 1931. Serial No. 549,631.

This invention relates to improvements in appliance plug clips or terminals.

An object of the invention is to generally improve the details of construction, assembly and operation of the parts of devices of the aforementioned character.

Another object is to provide a novel form of interlocking connection between the biasing spring and the sheet metal parts of the clip, whereby said parts are removably held in partially assembled relation independently of the binding screw.

Another object is to provide novel means for preventing undue separation of the sheet metal parts of the clip as by the prying action of an interposed jack blade.

Another object is to provide novel means for retaining the clip parts in completely assembled relation independently of the binding screw.

Another object is to provide a clip of the aforementioned character which is adapted for cooperation with substantially all different types of jack blades now used on electrical appliances.

Other objects and advantages of the invention will hereinafter appear.

The accompanying drawing illustrates certain embodiments of the invention which will now be described, it being understood that the invention is susceptible of embodiment in other forms without departing from the scope of the appended claims.

In the drawing, Figure 1 is an enlarged plan view showing the interior recesses in one of the duplicate sections of the longitudinally divided insulating casing which may be employed, a terminal clip constructed in accordance with my invention being positioned in one of the recesses.

Fig. 2 is a perspective view, in separated relation, of the clip parts shown in Fig. 1.

Fig. 3 is a side elevational view of the clip shown in Figs. 1 and 2.

Fig. 4 is a top plan view of a clip similar

to that shown in Figs. 1 to 3, but having a modified form of connection between the terminal parts of the clip.

Fig. 5 is a sectional view, on the line 5—5 of Fig. 4.

Fig. 6 is a perspective view showing the insulating sections of the casing in assembled relation to each other, but with the usual fastening bolts omitted for clarity of illustration.

Fig. 7 is a side elevational view similar to Fig. 3, but showing a slightly modified form of sheet metal clip parts and a modified form of biasing spring therefor.

Fig. 8 is a top plan view of the clip shown in Fig. 7, and

Fig. 9 is a top plan view of a further modified form of clip terminal.

Referring first to Figs. 1 to 3, the numeral 15 designates one of the duplicate molded sections of a longitudinally divided casing, the other section of which is indicated at 15^a in Fig. 6. Each of the sections 15 and 15^a is provided with a pair of interior recesses, the portions 16^a, 17^a of which are respectively adapted to accommodate the jack receiving portions of the clips and the portions 16^b, 17^b of which are respectively adapted to accommodate the wiring terminal portions of the clips,—said portions 16^a, 16^b and 17^a, 17^b being connected by reduced or neck portions 16^c, 17^c, respectively. The flat bottom walls of portions 16^b, 17^b of the recesses are provided with depressions, (one of which is shown at 16^d) to accommodate the shanks of binding screws.

The bottom walls of portions 16^a, 17^a of the recesses are of double-inclined or concave form, as indicated by the shading at 16^e and 16^f in Fig. 1. The forward ends of the portions 16^a, 17^a are inclined forwardly and downwardly as indicated at 16^g and 17^g toward the relatively deeper portions 16^b, 17^b, to accommodate the flared ends of the clips. The forward end walls of the sections

15, 15^a of the casing are provided with complementary grooves 18, 19 to accommodate jack blades of various cross sectional forms and dimensions.

5 Sections 15, 15^a are each likewise provided with a cord recess or groove 20 which is provided with meandering branches 20^a, 20^b leading to the respective binding screws of the clips. Grooves 20 may be enlarged as 10 indicated at 20^c, 20^d to accommodate the usual form of coiled wire cord-guard or the like. The exterior of the casing sections may be of any desired conformation, but as 15 illustrated the same embodies the design illustrated in my Design Patent No. 84,200, dated May 19, 1931.

The connector clip assemblies to be housed within the casing sections are of identical form, and as shown in Figs. 1, 2 and 3 each 20 assembly may comprise a pair of punched and stamped sheet metal members 21 and 22. Member 21 is provided with a flared end 23 which merges into the concave recess or groove 24 extending longitudinally thereof. Extending laterally of the groove 24 are a pair of flanges 25, 26, which flanges are respectively provided with notches 25^a, 26^a adjacent to the forward ends thereof. The neck portion 27 of member 21 is angled 25 upwardly therefrom and is integrally connected with the wiring terminal portion 28. Portion 28 is provided with a substantially centrally located tapped opening 28^a which is surrounded by the downwardly extending 30 flange 30, as best shown in Fig. 3. Portion 28 is provided on opposite sides thereof with parallel upstanding flanges 28^a, 28^b—the flange 28^b being notched or cut away, as indicated at 28^c for a purpose to be described.

40 Member 22 as shown is likewise provided with a flared end 29 and a groove the outer convex wall of which is shown at 30. Flanges 31 and 32 extend laterally from said groove, and said flanges are notched as indicated at 31^a and 32^a. Neck portion 33 is angled downwardly as shown and the same is integrally connected with the terminal portion 34. Portion 34 is relatively narrower than the portion 28 and is loosely insertable between the flanges 28^a, 28^b aforementioned,—said portion 34 being provided with an opening 35 of relatively larger diameter than the opening 28^c whereby clearance for the shank of a binding screw 36 is provided.

55 The biasing spring of the clip is of substantially U-shape as shown and comprises a straight connecting portion 37 which is adapted to be loosely positioned between the neck portions 27, 33 of members 21 and 22. 60 Offset upwardly from portion 37 and then bent downwardly to extend in a plane crossing the plane of the latter is an arm portion 37^a which overlies the upper surface (Fig. 2) of flange 25,—the downwardly angled free end portion 37^b of said arm being

adapted to extend through the notch 25^a. Offset downwardly from portion 37 and then bent upwardly to extend in a plane crossing the plane of said portion 37 is a second arm portion 37^c which underlies the flange 70 26 and the free end portion 37^d of which is angled upwardly to extend through the notch 26^a. With the spring arranged as illustrated in Fig. 2 a sub-assembly of the parts may be effected by inserting the flange 75 31 of member 22 beneath the spring arm 37^a with consequent engagement of the walls of notches 31^a, 32^a with the spring ends 37^b, 37^d, respectively. By pressing or forcing the terminal portion 34 laterally against the bias 80 of the spring the left-hand side (Fig. 2) of said portion may be caused to clear the flange 28^b on terminal portion 28. Portion 34 as shown is provided at the left-hand side thereof with an integral lug or projection 85 34^a, so that by depressing the former said lug may be caused to register with the aforementioned notch 28^c. The bias of the afore-described spring forces portion 34 toward the left with resultant interlocking engagement of projection 34^a with the walls of 90 said notch.

The sub-assembly thus effected may be handled and transported without danger of accidental separation of the parts, and at 95 any time as desired the binding screw 36 may be threaded into the tapped opening 28^a through the clearance opening 35 provided in portion 34. When screw 36 is driven home the portion 34 is pressed flat 100 against the portion 28 whereby the degree of torsion or pressure of the spring arms is slightly augmented in the finally assembled condition of the parts.

The terminal portions 28, 34 of each clip 105 fit within the complementary recesses 16^a and the complementary recesses 17^b of the casing sections, said terminal portions having a slight degree of lost motion both longitudinally and laterally of the casing sections whereby connection of the clips with and detachment thereof from jack blades of different shapes, dimensions and spacing is facilitated, it being noted that the complementary recesses 16^a, 17^a are likewise 110 shaped and dimensioned to permit the requisite degree of lost motion of the clips within the casing.

The casing sections are provided at spaced points with openings 38 and 39 the outer 115 ends of which are each preferably provided with countersinks or recesses 38^a, 39^a of hexagonal or other polygonal contour,—certain of said recesses being adapted to accommodate nuts of corresponding shape and the 120 other recesses being adapted to accommodate the heads of securing bolts or screws of suitable shape and size.

It will be noted that the angled free ends 37^b, 37^d of the spring arms engage the in- 125

ner walls of the respective alined pairs of notches 25^a, 31^a and 26^a, 32^a to resist lateral movement or misalignement of members 21 and 22 relatively to each other. On the other hand, said free ends 37^b, 37^d are subject to and adapted for lateral flexing in the event of insertion of jack blades of relatively great width. Moreover, by the arrangement illustrated the angled ends 37^b, 37^d are adapted 10 to engage the diagonally opposite end walls of alined notches 25^a, 31^a and 26^a, 32^a whereby undue separation of members 21 and 22, as by the prying action of a jack blade during removal of the connector therefrom, 15 is yieldably resisted.

The connector clip illustrated in Figs. 4 and 5 is substantially like that shown in Figs. 1 to 3. In this form, however, the upper member 22^x is provided with a terminal portion 34^x of slightly greater width than the portion 34^a aforescribed, and the projection 34^a of Figs. 1 to 3 has been omitted. Portion 34^x fits rather snugly between the upstanding lugs 28^y and 28^z formed integrally with the terminal portion 28^x, the opposite ends of said lugs being beveled as shown, and said beveled ends being bent or spun inwardly as shown to overlie the opposite edges of portion 34^x whereby the clip 25 parts are permanently secured in assembled 30 relation to each other. A tool (not shown) having a rotatable head with a conical or hemispherical cavity may be employed to effect the bending or spinning operation 35 aforementioned.

Also as will be noted the tapped opening 29^x in portion 28^x is provided with an upstanding surrounding flange 30^x, whereby a smooth lower surface is provided upon the 40 portion 28^x. This arrangement insures proper seating of the terminal portions 28^x of the clips within the recesses 16^b and 17^d of the insulating casing sections.

The device shown in Figs. 7 and 8 is substantially like that shown in Figs. 1 to 3, and corresponding parts have been given like characters of reference. In this form, however, the free end portions 37^x, 37^y of the spring have been bent in opposite directions with respect to each other and at substantially right angles to their respective arm portions 37^a and 37^c. Moreover, the notches in flanges 25, 26, 31 and 32 are of decreased length, as indicated at 26^x, 31^x and 32^x. In this form separation of the clip parts 21 and 22 is yieldably resisted by the resiliency of the neck portions 27 and 33 and by the resiliency of the spring arms 37^a and 37^c, but there is no definite engagement 55 of the free end portions 37^x and 37^y with the end walls of the notches as in the arrangements aforescribed. The walls of recesses 16^a and 17^a of the casing sections will, however, prevent undue separation of 60 the clip parts and said free end portions 37^x

and 37^y of the spring will be retained within the aforescribed notches in all relative positions of the clip parts.

The clip illustrated in Fig. 9 is substantially like that shown in Figs. 4 and 5, except that the lugs 28^y and 28^z are not offset inwardly over the terminal portion 34^x. On the other hand, the bias of spring 37 is utilized to effect movement of said terminal portion laterally against the lug 28^z whereby the clip parts are removably retained in partially assembled relation independently of the binding screw 36 aforesaid.

The binding screw 36 may be staked or its threads otherwise upset in any well known manner to prevent accidental removal thereof from the clip after complete assembly of the parts.

What I claim as new and desire to secure by Letters Patent is:

1. An appliance plug terminal comprising upper and lower terminal plates of substantially equal length adapted to receive between them a cooperating jack, said lower plate being provided with a tapped opening for cooperation with the shank of a binding screw and said upper plate being provided with a relatively larger opening to provide clearance for said shank, said lower plate also having upturned flanges at one end thereof, said upper plate having a relatively narrower end portion insertable between said flanges, and a substantially U-shaped spring having an intermediate portion thereof loosely positioned between said plates and having arm portions thereof located on opposite sides of said plates respectively, said spring acting to bias said plates toward each other and to bias said relatively narrower end laterally against one of said flanges whereby said parts are held in partially assembled relation and against accidental separation from each other prior to attachment of the binding screw.

2. An appliance plug terminal comprising a pair of opposed terminal plates of substantially equal length, said plates having complementary grooves for cooperation with a jack blade, the lower plate having an end portion provided with a flat lower surface, said end portion having an upwardly flanged tapped opening for cooperation with the shank of a binding screw, the upper plate having a flat end portion provided with a relatively larger opening to accommodate said flange, said first mentioned end portion also having a pair of upstanding lugs between which said second mentioned end portion is adapted to be received, and a substantially U-shaped spring having an intermediate portion thereof loosely positioned between said plates, the arm portions of said spring being stressed during assembly of the parts to provide for positioning of said arm portions on opposite sides of said plates re-

spectively, the stressed condition of said spring resulting in biasing of said second mentioned end portion into interlocking engagement with one of said lugs, whereby said parts are maintained in partially assembled relation.

3. An appliance plug terminal comprising a pair of opposed terminal plates of substantially equal length, said plates having complementary grooves for cooperation with a jack blade, the lower plate having an end portion provided with a flat lower surface, said end portion having an upwardly flanged tapped opening for cooperation with the shank of a binding screw, the upper plate having a flat end portion provided with a relatively larger opening to accommodate said flange, said first mentioned end portion also having a pair of upstanding lugs between which said second mentioned end portion is adapted to be received, and a substantially U-shaped spring having an intermediate portion thereof loosely positioned between said plates, the arm portions of said spring being stressed during assembly of the parts to provide for positioning of said arm portions on opposite sides of said plates respectively, the stressed condition of said spring resulting in biasing of said second mentioned end portion into interlocking engagement with one of said lugs, said second mentioned end portion having a projection and said last mentioned lug having a notch to receive said projection whereby all of said parts are positively retained in assembled relation prior to attachment of the binding screw.

4. As an article of manufacture, a two-part metal socket for appliance plugs, said metal parts having complementary grooves for the reception of a jack blade there between, longitudinally extending flanges at opposite sides of said grooves, said flanges having notches formed therein adjacent to the forward ends thereof respectively, and a substantially U-shaped spring, the intermediate portion of said spring being located between said metal parts at the rear ends of said grooves respectively, the arms of said spring being arranged to engage a diagonally opposed pair of said flanges in the assembled relation of the parts, said intermediate portion of the spring being stressed by the assembly of the metal parts whereby the latter are biased toward each other.

5. As an article of manufacture, a two-part metal socket for appliance plugs, said metal parts having complementary grooves adapted for reception of a jack blade there between, longitudinally extending flanges at opposite sides of said grooves, said flanges having notches formed therein adjacent to the forward ends thereof respectively, a substantially U-shaped spring, the intermediate portion of said spring being located be-

tween said metal parts at the rear ends of said grooves respectively, the arms of said spring being arranged to engage a diagonally opposed pair of said flanges in the assembled relation of the parts, said intermediate portion of the spring being stressed by the assembly of the metal parts whereby the latter are biased toward each other, one of said metal parts having an end portion provided with upstanding parallel flanges, the other metal part having an end portion fitting loosely between said flanges, said spring acting to bias said last mentioned end portion laterally into engagement with one of said last mentioned flanges to thereby retain said spring and said metal parts in partially assembled relation, and a wiring terminal screw the shank of which has threaded engagement with one of said end portions and the head of which is adapted for clamping engagement with the other of said end portions, whereby a good mechanical and electrical connection between said metal parts is provided.

6. As an article of manufacture, a two-part metal socket for appliance plugs, said metal parts having complementary grooves adapted for reception of a jack blade there between, longitudinally extending flanges at opposite sides of said grooves, said flanges having notches formed therein adjacent to the forward ends thereof respectively, a substantially U-shaped spring, the intermediate portion of said spring being located between said metal parts at the rear ends of said grooves respectively, the arms of said spring being arranged to engage a diagonally opposed pair of said flanges in the assembled relation of the parts, said intermediate portion of the spring being stressed by the assembly of the metal parts whereby the latter are biased toward each other, one of said metal parts having an end portion provided with upstanding parallel flanges, the other metal part having an end portion fitting loosely between said flanges, said spring acting to bias said last mentioned end portion into engagement with one of said last mentioned flanges to thereby retain said spring and said metal parts in partially assembled relation, and a binding screw penetrating one of the aforementioned end portions of said metal parts and having threaded engagement with the other of the same to retain said spring and said metal parts in completely assembled relation.

7. As an article of manufacture, a terminal socket for appliance plugs, said socket comprising a pair of punched and stamped sheet metal members having complementary grooves to accommodate a jack blade there between, said members each having laterally extending flanges on opposite sides of the respective grooves, said flanges being provided with aligned notches adjacent to the

forward ends of said members, a substantially U-shaped spring having its intermediate portion loosely positioned between said members, and the arms of said spring being offset with respect to said intermediate portion and extending in planes crossing the plane of said intermediate portion, said arms engaging diagonally opposed flanges on the respective sheet metal members whereby the latter are biased into socket forming relation, the free ends of the spring arms being bent to extend in opposite directions through the respective pairs of alined notches, said spring ends acting to prevent lateral placement of said members with respect to each other in the normal plane of contact thereof while permitting separation thereof in directions at right angles to said plane during engagement thereof with a jack blade.

8. As an article of manufacture, a terminal socket for appliance plugs, said socket comprising a pair of punched and stamped sheet metal members having complementary grooves to accommodate a jack blade therebetween, said members each having laterally extending flanges on opposite sides of the respective grooves, said flanges being provided with alined notches adjacent to the forward ends of said members, a substantially U-shaped spring having its intermediate portion loosely positioned between said members, and the arms of said spring being offset with respect to said intermediate portion and extending in planes crossing the plane of said intermediate portion, said arms engaging diagonally opposed flanges on the respective sheet metal members whereby the latter are biased into socket forming relation, the free ends of the spring arms being bent to extend in opposite directions through the respective pairs of alined notches, said spring ends cooperating with certain of the walls of said alined notches to retain said members in superimposed alinement with each other in all relative positions of the latter, said spring ends also cooperating with other walls of said notches to limit the degree of separation of said members, for the purpose set forth.

9. As an article of manufacture, a terminal socket for appliance plugs, said socket comprising a pair of punched and stamped sheet metal members having complementary grooves to accommodate a jack blade therebetween, said members each having laterally extending flanges on opposite sides of the respective grooves, said flanges being provided with alined notches adjacent to the forward ends of said members, a substantially U-shaped spring having its intermediate portion loosely positioned between said members, and the arms of said spring being offset with respect to said intermediate portion and extending in planes crossing the

plane of said intermediate portion, said arms engaging diagonally opposed flanges on the respective sheet metal members whereby the latter are biased into socket forming relation, the free ends of the spring arms being bent to extend in opposite directions through the respective pairs of alined notches, said spring ends cooperating with certain of the walls of said alined notches to retain said members in superimposed alinement with each other in all relative positions of the latter, said spring ends also cooperating with other walls of said notches to yieldably limit the degree of separation of said members, for the purpose set forth.

10. As an article of manufacture, a biasing spring for two-part metal socket terminals of appliance plugs and the like, said spring being of substantially U-shape, the intermediate portion of said spring being straight and the arms of said spring being offset in opposite directions with respect to said intermediate portion, said arms being bent in opposite directions to extend in planes crossing the plane of said intermediate portion, and the free ends of said arms being additionally bent in directions corresponding to the first mentioned bends respectively to provide for interlocking engagement of said spring with cooperating parts of a socket terminal.

11. As an article of manufacture, a biasing spring for two-part metal socket terminals of appliance plugs and the like, said spring being of substantially U-shape, the intermediate portion of said spring being straight and the arms of said spring being offset in opposite directions with respect to said intermediate portion, said arms being bent in opposite directions to extend in planes crossing the plane of said intermediate portion, and the free ends of said arms being additionally bent in directions corresponding to the first mentioned bends respectively to provide for interlocking engagement of said spring with cooperating parts of a socket terminal, said spring arms being distorted from the initial planes thereof into approximately parallel planes by the assembling operation, whereby the socket parts are biased toward each other.

12. An appliance plug terminal comprising upper and lower terminal plates of substantially equal length formed to yieldably accommodate a jack blade between them, said lower plate having an end provided with a tapped opening for cooperation with the shank of a binding screw and said upper plate having an end provided with a relatively larger opening to provide clearance for said shank, said lower plate also having upstanding lugs on opposite sides of the aforementioned end thereof, the end of said upper plate being relatively narrower for reception thereof between said lugs, and a

substantially U-shaped spring having an intermediate portion thereof located between said plates, the arm portions of said spring being normally biased against opposite sides of said plates respectively, said parts coacting to releasably retain each other in assembled relation, and said lugs being upset inwardly to clampingly engage said relatively narrower end portion, whereby all of said parts are permanently secured in assembled relation to each other.

In witness whereof, I have hereunto subscribed my name.

GEORGE J. MEUER.
